UNITED STATES PATENT OFFICE.

ISAAC ELIE LECOULTRE, OF LAUSANNE, SWITZERLAND.

INTERRUPTER FOR ELECTRIC CIRCUITS.

SPECIFICATION forming part of Letters Patent No. 399,057, dated March 5, 1889.

Application filed September 21, 1887. Serial No. 250,237. (No model.) Patented in Belgium March 15, 1887, No. 76,612.

To all whom it may concern:

Be it known that I, ISAAC ELIE LECOULTRE, of Lausanne, Switzerland, have invented a new and useful Improvement in Interrupters for Electric Circuits, (for which a patent was granted in Belgium, No. 76,712, March 15, 1887,) of which the following is a specification.

Figure 1 is a cross-section through the interrupter when the same is in the position in which it closes the circuit. Fig. 2 is a cross-section of the same when the current is interrupted. Fig. 3 is a plan view of the apparatus after having withdrawn the cover B. Fig. 4 is a cross-section of the cover B, spring F, and piston C. Fig. 5 is a vertical section of a modified interrupter of the same general character. Fig. 6 is a section through the cover B' of Fig. 5. Fig. 7 shows an inverted plan view of said cover without piston C and spring F', and Fig. 8 an inverted plan view of the cover with piston C and spring F'. Fig. 9 is a plan view, and Fig. 10 a cross-section, of plate A', and Fig. 11 is a plan view of spring F'. Fig. 12 is a base-plate of insulating material, and fixed to the wall or other support by means of screws a' and a².

Upon plate A there is fixed, by means of screws d, a metallic segment, D, and a metallic segment, E, placed symmetrically to the first one and secured by means of screws e.

Screw f of segment D and screw g of segment E act as binding-screws, to which are affixed the two ends of the wires entering the apparatus through the hole A².

Over the plate A is screwed a cover, B, of non-conducting material, through which passes the stem of the piston C, by which the electric contact between the plates D and E is established. A spring, F, as viewed edge-wise, is in form a flat loop or bow having free ends similar to a horseshoe, as shown in Figs. 4 and 11, and the same is fixed at its central portion by means of one or more screws, h' h², to the cover B. The two extremities of said spring bear against the sides of the piston C, which is provided with a non-metallic or insulating friction-ring, c', which is between the arms of the spring F when the piston C is moved from the position shown in Fig. 1 into the position shown in Fig. 2; or, vice versa, the said ring c' prevents at the same time the displacing of piston C as long as the latter is not acted upon by hand against the button-head c². The piston C has a coni-

cal head corresponding to concavities in the adjacent edges of the plates D and E.

In the modification shown by the Figs. 5 to 11 the segments D and E are fixed to the cover B', and spring F' is provided with a projection intended to be screwed to D. The segments D and E are provided with metallic projections d' and e', and the plate A' has corresponding metallic bands d² and e², to which are affixed the both ends of the electric-circuit wire. The cover B' is placed over A', so as to have d' connected to d² and e' connected to e². The screws G and H are then turned so as to have d' pressed against d² and e' against e².

In all cases the inner surfaces of the opposing free ends of the spring F adjacent to the conical head are rounding or concave, so as to take an even frictional bearing against the exterior surface of the conical head, and by the springs the conical head will be securely held in place either in contact with the circuit-closing plates in completing the circuit or away from them in breaking the circuit, and the spring, being bent into a horseshoe form, is not liable to be broken, and the parts are strong and reliable.

I claim as my invention—

1. The combination, with the base and cover of insulating material, the metallic segments upon the base, and a movable piston, of a flat, bent, or loop-shaped friction-spring secured at its central portion to the cover, and having its free opposing ends curved to frictionally grasp and hold the piston, substantially as specified.

2. The combination, with the base and cover of insulating material, of the metallic segments D E upon the base, and the electric connections to the said segments, a movable piston for making and breaking the electric circuit, and a stem to the same passing through the insulated cover, and a button-head, c², a bent or loop friction-spring connected to the cover and having curved or concave opposing free ends engaging the piston widthwise at opposite sides and acting to maintain the same in its various positions, and a ring, c', connected to and acting to prevent the displacement of the piston, substantially as set forth.

ISAAC ELIE LECOULTRE. [L. S.]
